ABSTRACT

A fluidic high pressure hydraulic pulsator including vortex amplification in a power jet stage and vortex shear modulation in a feedback control stage. Discharge from the supply-jet-receiving chamber of a vortex amplifier is made to alternate automatically between its power jet output orifice and a vortex release chamber utilized for vortex shear modulation of the tangentially introduced control jet of such amplifier.

FLUIDIC HIGH PRESSURE HYDRAULIC PULSATOR

BACKGROUND OF THE INVENTION

This invention relates to a feedback-controlled fluidic pulsator particularly useful for obtaining hydraulic pulses of relatively high pressure, and flow rate up to thousands of p.s.i. and 25 g.p.m., for example.

Repetitive high pressure hydraulic pulses are currently being contemplated, investigated and/or employed; for fracturing rock, mineral ores, etc., as in mining; for agitation of solutions, as in cleaning; for piston-implemented vibratory actuation of hammering and cutting tools, such as pile drivers, plows, trenchers, etc., as in construction and earth handling; and for numerous other uses.

Heretofore, insofar as applicant is presently aware, the obtaining of repetitive hydraulic pulses of any significant power level have employed mechanical valves, and such valves tend to be bulky and are prone to experience the usual mechanical wear.

SUMMARY OF THE INVENTION

The high-pressure high-power hydraulic pulsator of the present invention, in being purely fluidic in essence of its operation, overcomes size and wear limitations inherent in mechanical valves, and affords added opportunity for advancement of hydraulic pulsed jet techniques in mining and other fields. In accord with the present invention by the employment of the vortex release fluid from a vortex amplifier to shear modulate the tangential control jet of such amplifier, a high gain is realized which is sufficient to assure realization of a rapid rate of pulsation of the power jet output of such amplifier as well as full turn-off of such power jet between pulses, if desired.

Further, by utilizing the fluid vortex released from the vortex amplifier for shear modulation of the input control jet for such amplifier, an extremely compact arrangement of casing components is afforded.

Still further, by controlling the fluid transmission characteristics of the control fluid feedback path to the vortex amplifier, the pulsation rate, hence turn-on and turn-off times of the output pulses, can be altered to suit particular operating conditions that may be desired.

Other features and advantages of the present invention will become apparent from the following more detailed invention.

thereof, taken in connection with the accompanying drawings which illustrate the best mode presently contemplated for carrying out the invention.

BRIEF DESCRIPTION OF THE DRAWINGS

FIG. 1 is a flow diagram of the present invention;

FIG. 2 is a longitudinal section view of a preferred embodiment of the invention and in single output form;

FIG. 3 is a transverse section view taken along the line III-III in FIG. 2;

FIG. 4 is a transverse section view taken along the line IV-IV in FIG. 2; and,

FIG. 5 is a longitudinal section view of a dual output pulsator employing two integrally joined pulsators of FIG. 2 form connected back-to-back and cross-coupled control wise to obtain automatic switching of the power jet output alternately between the two outputs.

DESCRIPTION OF ILLUSTRATED EMBODIMENTS

The reference numerals employed herein coincide with those employed to designate similar components disclosed and described in U.S. Pat. No. 3,520,317 issued to the Administrator of the National Aeronautics and Space Administration on a shear-modulated vortex amplifier invention of the same inventor as that of the present invention. Reference may be had to such Patent for further understanding of the present invention, as well as to NASA Technical Memorandum TMX-53539 of Nov. 14, 1966; the present invention, however, was not made under a NASA contract and is not the property of the U.S. Government,

Referring to FIGS. 1 to 4, inclusive, construction and operation of the single-output form of the present invention is as follows:

Output from a hydraulic output jet supply source 19 at such as 3,000 p.s.i. flows to a circular chamber 33 in a vortex amplifier portion 13 by way of supply-jet-input passage means 34 and input port means 35, from which such fluid discharges through an amplifier discharge port 37 either axially across a gap 37a into a power jet output orifice 38 aligned with such port 37 or radially and circumferentially outward into a cylindrical vortex release chamber 25 encircling such gap 37a; according to the presence or absence of a significant degree of vortex action imparted on such fluid flow by a control jet introduced tangentially into chamber 33 via control jet input means 36, including an annular chamber 36a encircling chamber 33 and a series of circumferentially spaced-apart ports 36b opening tangentially inward into such chamber 33.

In accord with the present invention, the presence or absence of such significant degree of vortex action in chamber 33 is determined by corresponding significant degrees of change in vortex flow action in the vortex release chamber 25 by utilizing such action to shear-modulate flow of control jet fluid supplied to the control jet input means 36 via a control jet delivery passage 15 and a control-jet-receiving port 30 aligned with a control jet-supply port 29 at the opposite side of a gap 27 via which the swirling fluid in release chamber 25 travels enroute to a return port 31 for release and return to the inlet of pump means (not shown) that furnishes hydraulic fluid under suitable pressure to the output jet supply source 19 and to a control jet supply source 17 connected to the port 29. The direction of vortex swirl in the release chamber 25 is opposite to the direction of travel of the control jet stream leaving port 29, so that discharge of fluid from chamber 25 greatly influences the direction of travel of such control jet stream and rapidly deflects it out of registry with receiving port 30 to cut off or significantly diminish supply of control jet fluid to the amplifier chamber 33 via tangential control jet input means 36.

Since significant reduction in control jet input to the vortex amplifier chamber 33 via means 36 results in discharge of amplifier output into power jet output orifice 38 and cutoff of amplifier output discharge into vortex release chamber 25, which in turn calls for increase in control jet input to chamber 33 via means 36, it will be seen that the amplifier device will not operate in any one state, but automatically alternates its discharge flow between power jet output orifice 38 and vortex release chamber 25; with either complete or in-

complete cutoff at orifice 38 being realized according to operating parameters of the system including fluid flow characteristics of the feedback path for the control jet, which may be altered to suit desired operating conditions, such as by controlling its degree of restriction and by addition of accumulator chamber means to vary the timing of feedback.

Since modulation of the control jet delivered to amplifier chamber 33 via jet receiving port 30 is highly efficient, the rate of automatic pulsating operation of the system can be relatively rapid, if desired, and the turn-on and turn-off of each power jet output pulse also can be rapid, in effect a square wave pulse shape, rather than sinusoidal, which can be of significance in such hydraulic jet uses as mining where jet impulse and disintegrating action can be enhanced by such rapid changes in jet flow.

Referring now to FIG. 5, two pulsator devices similar to that of FIG. 2 are connected back-to-back, but instead of connecting the control jet receiving port 30 of each to its own tangential control jet input means 36, the receiving port 30 of one is connected to the control jet input means 36 of the other. By virtue of this arrangement it will be readily apparent that power jet output can be made to alternate automatically between the two power jet output orifices 38; an arrangement which may be of advantage in certain uses.

While the foregoing description of the invention has been related to its use with hydraulic fluid under pressure it will be apparent that it can function also with use of a compressible fluid under pressure.

As illustrated in the several figures of the drawing, numerous chambers, passages, ports, etc. are formed in portions of a casing means to afford strength for high pressure use, and such portions are suitably divided to afford necessary fabrication and assembly. A detailed description of the precise shapes of such casing portions is not deemed either necessary or desirable with respect to an understanding of the present invention.

I claim as my invention:

1. A fluidic pulsator comprising, a vortex amplifier means operable during flow of power fluid under pressure therethrough to discharge such fluid under pressure alternatively into a power jet output orifice means or into a vortex release chamber means according to relative propensity for such flow to travel axially or circumferentially, respectively, and a vortex shear modulator means operable by vortex fluid under pressure from said vortex release chamber means to effect supply of control jet fluid under pressure to said vortex amplifier means to impart circumferential flow characteristics to the flow of power fluid under pressure passing therethrough in inverse proportion to flow of fluid under pressure into said vortex release chamber means.
2. A fluidic pulsator comprising means defining, a vortex amplifier chamber means, an input passage means for introducing fluid under pressure into said vortex amplifier chamber means

in a manner which encourages axial flow of such fluid under pressure therethrough, control jet input passage means for introducing control fluid under pressure into said vortex amplifier chamber means in a manner which encourages circumferential flow of fluid under pressure therein, an amplifier discharge port means through which fluid under pressure in said vortex amplifier chamber means discharges, a power jet output orifice means axially spaced apart from and aligned with said amplifier discharge port means for receiving fluid under pressure therefrom according to its propensity for axial flow, a vortex release chamber means coaxial with and encircling the axial separation region between said power jet output orifice means and said amplifier discharge port means, to receive flow of fluid under pressure from said amplifier discharge port means according to its propensity for radial and circumferential flow due to vortex action imparted by control fluid flow into said vortex amplifier chamber means, release passage means opening radially outward from said vortex release chamber means via which fluid under pressure may escape therefrom, control jet receiving port means opening transversely into said release passage means for availing said control jet input passage means with fluid under pressure, control jet supply port means opening into said release passage means oppositely to said control jet receiving port means, whereby a jet stream of fluid under pressure leaving said control jet supply port means will be vortex-shear-modulation-deflected by fluid under pressure leaving said vortex release chamber means to control receipt of such jet stream by said control jet receiving port means in inverse proportion to flow of fluid under pressure into such vortex release chamber means.

3. A dual-power-output fluidic pulsator comprising, two vortex amplifier means operable during flow of power fluid under pressure therethrough to discharge such fluid under pressure alternatively into respective power jet output orifices or into respective vortex release chambers according to the presence or absence of a significant degree of circumferential swirling action within such power fluid streams upon exiting said vortex amplifiers, and two vortex shear modulator means operable by vortex fluid under pressure from said vortex release chambers, respectively, to effect cross-coupled supply of control jet fluid under pressure to said two vortex amplifier means to impart circumferential swirling action to the power fluid under pressure flowing therethrough in inverse proportion to such vortex release chamber means.
